UNITED STATES PATENT OFFICE.

WILLIAM W. WALTER, OF AURORA, ILLINOIS, ASSIGNOR OF ONE-THIRD
TO JAY D. MILLER, OF GENEVA, ILLINOIS.

VEHICLE AIR-BRAKE.

SPECIFICATION forming part of Letters Patent No. 761,618, dated May 31, 1904.

Application filed January 23, 1903. Serial No. 140,241. (No model.)

To all whom it may concern:

Be it known that I, WILLIAM W. WALTER, a citizen of the United States, residing at Aurora, in the county of Kane and State of Illinois, have 5 invented certain new and useful Improvements in Vehicle Air-Brakes, of which the following is a specification.

The invention relates to air-brakes, being specially designed for railway use and for road- 10 vehicles; and it consists in certain novel combinations and arrangements of parts with the view of simplifying, economizing, and otherwise improving the operation of apparatus of this class.

15 The nature, characteristic features, and scope of the invention will be more clearly apparent from the following detailed description, taken in connection with the accompanying drawings, forming a part hereof, wherein—

20 Figure 1 is a top view, partly in section, of an air-brake apparatus embodying features of the invention, the parts being shown in their general operative relation with the pump in the act of compressing and storing air. Fig.

25 2 is a similar view of the brake slightly modified in part to adapt it for use in connection with a wagon or other road-vehicle, and the illustration is sufficiently comprehensive to disclose the relation. Fig. 3 is a sectional top 30 view of the compressing-cylinder, air-reservoir, and pumping mechanism, the latter being represented shifted out of operative relation, due to an excess of pressure in the reservoir; and Fig. 4 is a detail of the eccentric for 35 actuating the pump mechanism.

Referring to the drawings, and in the first instance to Fig. 1, *a* designates a car-axle provided with a wedge or inclined projection *b*.

c designates an eccentric adapted to be carried by the axle and its projection and arranged to be shifted in respect to the latter. The yoke *d*, which encircles the eccentric, carries one end of a pump-rod *e*, the other end of said rod being pivoted or otherwise mov- 45 ably secured to a piston-rod *f*, as at *e'*, so that said pump-rod may follow or be shifted with the eccentric. The piston-rod *f* carries a piston *f'*, arranged to be reciprocated in a cylinder *g*, the interior of said cylinder being di-

vided by a partition *g'* into a pumping or compressing cylinder *h*, in which the piston operates, and an air-reservoir *h'*.

i *i'* are air-inlet ports provided in the walls of the compressing-chamber and controlled by check-valves *i*². There is a port *j* in the partition *g'*, controlled by a check-valve *j'*, affording communication between the pump-cylinder and reservoir, and there is an air-pipe *k* connecting said pump-cylinder and reservoir and provided on the pump side with a check-valve *k'*, so that, as will be observed, the piston is double-acting, or, in other words, pumps and stores air at each stroke forward and backward.

Means are provided for shifting the pump-rod and eccentric or throwing them out of operative relation with the pump at a predetermined moment—*i. e.*, when sufficient air has been compressed or stored in the reservoir *h'*. Said means comprise a spring *l*, suitably 65 mounted in a wall of the air-reservoir and arranged to be adjusted to any predetermined pressure by means of set-screws *l'*. The spring *l* is mounted in relation to a piston *m*, whose rod *m'* is attached to a shifting-lever *n*, operatively connected with the pump-rod *e*, for example, by means of a sleeve *n'*. It will thus be observed that when the pressure in the reservoir exceeds that at which the spring *l* has been adjusted the piston *m* will be shifted 70 and will cause the rod *n* to shift the pump-rod *e*, and with it the eccentric *c*, to an inoperative position in respect to the pump. It will 75 likewise be apparent that when the pressure in the reservoir is relieved the spring *l* will solicit the piston *m* to its former position, thereby returning the shifting-rod *n* and its connected parts to their normal positions.

The brake-cylinder is designated at *o*, and it is provided with the complementary piston *o'* *o'*, the latter carrying the usual brake-beam *p*. A spring *o*³ or the equivalent thereof tends to hold the brake-beam away from the wheels when the brake is not in use. A pipe *q* affords communication between the reservoir *h'* and the brake-cylinder, and said pipe is provided at some intermediate point with valve *q'*, which is arranged to be opera-

ted by a disk or member r , which also operates the relief-valve s of the brake-cylinder.

t designates the brake-lever, which may be connected in any appropriate manner with the disk or member r .

In the illustration Fig. 2 the invention is shown in connection with a road-vehicle, and as the axle of the latter, as a general rule, does not rotate, the projection b' is applied to the hub x of one of the wheels. Another slight modification to which attention may be called is the link c' , which is pivoted to a stationary part of the pump-cylinder and constitutes the movable connection between the pump-rod 15 and the pump-cylinder piston.

It will be obvious to those skilled in the art to which the invention appertains that modifications may be made in details without departing from the spirit and scope of the invention. Hence I do not limit myself to the precise construction and arrangement of parts hereinabove described, and illustrated in the accompanying drawings; but,

Having described the nature and object of the invention, what I claim as new, and desire to secure by Letters Patent, is—

1. The combination in an air-brake apparatus for vehicles, of a brake-cylinder, its piston and piston-rod, an air-reservoir and an air-compressing cylinder integral together, and a valved partition between them, a pipe leading from the reservoir to the brake-cylinder, and a pipe leading from the compressing-cylinder into the reservoir, and means to receive

air into the cylinder and compress it, substantially as described.

2. The combination in an air-brake apparatus for vehicles, of a brake-cylinder, its piston and piston-rod, an air-reservoir and an air-compressing cylinder integral together, and a valved partition between them, a pipe leading from the reservoir to the brake-cylinder and a pipe leading from the compressing-cylinder into the reservoir, a spring-piston and its stem in the side of the reservoir, a pivoted lever having one end in engagement with said stem, the air-compressing piston, its rod, and its hinged connecting-rod, and a sleeve carried by the pivoted lever, substantially as described.

3. The combination in an air-brake apparatus for vehicles, of a brake-cylinder having a relief-valve in one end, an air-reservoir and an air-compressing cylinder integral together, and a valved partition between them, a pipe leading from the reservoir to the brake-cylinder, a valve upon said pipe, a disk carrying the stem of said valve and also the stem of the relief-valve of the brake-cylinder, and means to operate said disk and valves, substantially as described.

In testimony whereof I affix my signature in presence of two witnesses.

WILLIAM W. WALTER.
